DESIGN FOR A PLATE

Jacques C. De Kort, Trenton, N. J., assignor to Scammell China Company, Trenton, N. J.

Application December 23, 1940, Serial No. 97,574

Term of patent 3½ years

To all whom it may concern:

Be it known that I, Jacques C. De Kort, a citizen of the United States, residing at Trenton, in the county of Mercer and State of New Jersey, have invented a new, original, and ornamental Design for a Plate, of which the following is a specification, reference being had to the accompanying drawing, forming part thereof.

The figure is a plan view of a plate, showing my new design.

I claim:

The ornamental design for a plate, as shown.

JACQUES C. DE KORT.
